[57] **CLAIM**

The ornamental design for a vehicle wheel center, as shown and described.

DESCRIPTION

FIG. 1 is a perspective view of a vehicle wheel center showing my new design, it being understood that the broken lines are for illustrative purposes only;

FIG. 2 is a front elevational view thereof;

FIG. 3 is a sectional view taken along line 3—3 in FIG. 2;

FIG. 4 is a sectional view taken along line 4—4 in FIG. 2;

FIG. 5 is a sectional view taken along line 5—5 in FIG. 2;

FIG. 6 is a sectional view taken along line 6—6 in FIG. 2;

FIG. 7 is a perspective view of a vehicle wheel center showing a second embodiment of my design wherein the sole difference resides in the shape of the bolt holes, it being understood that the broken lines are for illustrative purposes only.
